UNITED STATES PATENT OFFICE.

HERBERT S. NESBITT, OF MINNEAPOLIS, MINNESOTA, ASSIGNOR OF ONE-THIRD TO OSCAR P. GUSTAVSEN, OF MINNEAPOLIS, MINNESOTA, AND ONE-THIRD TO THOMAS D. McMAHON, OF ST. PAUL, MINNESOTA.

GRAIN DOOR FOR CARS.

Application filed July 10, 1922. Serial No. 573,865.

To all whom it may concern:

Be it known that I, HERBERT S. NESBITT, a citizen of the United States, residing at Minneapolis, in the county of Hennepin and State of Minnesota, have invented certain new and useful Improvements in Grain Doors for Cars; and I do hereby declare the following to be a full, clear, and exact description of the invention, such as will enable others skilled in the art to which it appertains to make and use the same.

This invention relates to a car door structure and particularly to a door structure for a car adapted to contain grain or a similar bulk commodity. Grain is usually transported in a box car type of car and when the car is filled with grain there is great pressure against the doors thereof and the same are usually opened only with great difficulty.

It is an object of this invention, therefore, to provide a car door structure of simple construction which can be easily and quickly opened to discharge the grain.

It is a further object of the invention to provide such a car door structure comprising a door having a plurality of sections which, when not in use, can be easily and quickly disposed adjacent the roof of the car.

It is more specifically an object of the invention to provide a car door having a lower section provided with beveled plates at its sides adapted to be received in beveled notches in the door posts.

These and other objects and advantages of the invention will more fully appear from the following description made in connection with the accompanying drawings in which like reference characters refer to the same parts throughout the different views, and in which,

Fig. 1 is a view in front elevation of the door in closed position;

Fig. 2 is a vertical central section of Fig. 1;

Fig. 3 is a vertical section through the door showing the door sections in a different position;

Fig. 4 is a view in front elevation of one section of the door detached;

Fig. 5 is a partial plan view of one section of the door shown on an enlarged scale; and Figs. 6 and 7 are, respectively, horizontal

sections taken on the line 6—6 and 7—7 of Fig. 3, also shown on an enlarged scale. 55

Referring to the drawings, certain parts of a box car are shown, of which it will only be necessary to note the door posts or jambs 1, the top cross member 2, the floor 3 and the roof portion 4. The grain door 60

proper comprises a lower section A and an upper section B. The lower section A is shown as composed of a frame 5 of heavy material covered by panels 6 of thinner material, said panel portion being on the inside of the door. The side portions of the frame 5 have secured therein and projecting outwardly therefrom, a series of equally spaced headed bolts 7 and plates 8 are ex- 65

tended vertically along each side of said section and are provided with slots 9 through which the body portions of bolts 7 pass, the plates thus being slidable laterally between the heads of said bolts and the frame 5. The inner side edges of the plates 8 are 70

beveled inwardly, as clearly shown in Figs. 4 and 5. The said plates 8 are connected by sliding members 10 and 11 moving in strap guides secured to frame 5 to the outer ends of links 12. As clearly shown in Fig. 5, 75

plates 8 are formed on their inner surface with shoulders 8^a against which the flat ends of members 10 abut. The other ends of these links are provided with short slots 80

through which project headed bolts secured in an oval disk or plate 13 pivotally and centrally mounted on the frame 5 substantially centrally thereof. It will be clearly 85

seen from Figs. 3 and 5 that members 10 and 13 both have their inner surfaces in contact with the outer surface of member 5 and also have their outer surfaces in contact with the inner surfaces of the links 12. Members 10 and 13 will, therefore, be in 90

abutting relation when in the position shown in Fig. 1. A handle lever 14 is connected to the plate 13 and provided with a latching pawl 15 adapted to hook over and be held by a bolt or similar catch member 16 projecting from the lower portion of the frame 5. The section A also has secured 95

therein, at its upper corners, plates 17 from which headed bolts 18 project adjacent the upper corners thereof.

The door posts 1 are provided throughout 100 the lower portion of their opposed sides with 105

slots 19, the forward walls of which are inclined forwardly or toward the outer side of the car. The posts 1 are preferably covered with metal plates 20 extending along their opposed and inner sides and said plates are formed with cut and bent-in portions 21 forming openings at the front of slots 19, and bent to extend inwardly along the inclined wall of said slots. The posts 1 are also provided along the upper portion of their opposed sides with vertical grooves 22 preferably of rectangular cross section and the plates 20 are extended upwardly along the posts and provided with slots 23 of less width than the grooves 22 to form T-shaped openings. The plates 20 and grooves 22 incline inwardly at their upper ends and the same are provided with spaced outwardly projecting recesses 24 extending laterally from said slots.

The upper section B of the door is shown as formed of a frame 25 covered by panels 26 at the inner side thereof and said door is also provided at its upper corners with plates 27 formed with projecting headed members 28. The panel portion 26 of the section B extends below the frame 25 and is adapted to abut against the upper projecting portion of frame 5 of section A, the inner surface of the two sections thus lying flush with each other when the doors are in closed position, as shown in Fig. 2.

The projecting headed members 18 on the lower section A are normally disposed adjacent the bottom of the grooves 22 and said section can be swung outwardly on said members as trunnions, as clearly illustrated in Fig. 3. The upper section B when raised slightly to clear the lower section can also be swung outwardly about the projecting members 28. When the car is empty and the door sections A and B not in use, said sections may be moved upwardly by sliding the headed members 18 and 28 vertically in the grooves 22 and disposing said members in recesses 24. The doors can then be swung about said members into a substantially horizontal position adjacent the roof 4 of the car, in which position they are secured by latch members 29 and 30 pivotally mounted on said roof and which engage under the outer edges of said sections, as shown in Fig. 3.

When it is desired to load the car with grain or similar material the lower section A will be swung to closed position and the handle lever 14 turned to move the members 10 and 11 and the plates 8 into the grooves 19. The lever 14 can then be latched or locked in position by members 15 and 16 and the lower section A will thus be movably held in closed position. When the car is filled substantially to the top of said section the upper section B can be released and moved downwardly into closed position, as

shown in Fig. 2 and the car then further filled. When it is desired to unload the car the latch 15 will be disengaged and the lever 14 knocked slightly to the left from its closed position, as shown in Fig. 1. The pressure of the grain against the section A will press the beveled edges of plates 8 against plates 21 and this pressure will act to cam in the plates 8 so that when the lever 14 is moved but a slight distance the same will be quickly swung around by said pressure of the grain and the section A thus automatically released. The pressure of the grain will swing the lower portion of the door outwardly and the grain will thus be discharged. After a sufficient amount of grain has been discharged so that the level thereof is below the section B, this section can be swung upwardly to the position shown in Fig. 3 and after the grain has been still further discharged the section A can also be lifted and swung to its inoperative position. If the car be loaded with some material that does not have the fluid action of grain it will be necessary to manually swing the lever 14 to the position shown in Fig. 4 to release the lower section A.

From the above description it is seen that applicant has provided a simple and efficient grain door. The door can be easily and inexpensively installed on new cars, or the same can be quickly installed on old cars of standard type. It will simply be necessary to cut the slots or grooves 19 and 22 in the posts 1 and to add the protecting plates 20. The parts of the door are quite simple and can be easily manipulated, both to close the same and to open the car.

It will, of course, be understood, that various changes may be made in the form, details and arrangement of the parts without departing from the scope of applicant's invention, which, generally stated, consists in the matter shown and described and set forth in the appended claims.

What is claimed is:

1. A car door structure comprising door posts having vertical grooves in the lower portions of their adjacent sides, said grooves having their forward walls outwardly inclined, metal plates covering said sides of the posts and extending along said inclined walls, a door section disposed between said posts having laterally movable metal plates extending along its vertical side edges, the outer edges of said plates being beveled at their front portions to be disposed in said grooves and co-operating with the plates therein.

2. The combination with the door posts of a box car, of a door closure disposed therebetween comprising a lower door section, laterally movable plates extending longitudinally at each side thereof, the side edges of said plates being beveled at their front

portions and said door posts being provided with longitudinally extending vertical grooves having inclined front portions with which said plates are adapted to co-operate, 5 whereby a cam action occurs between said beveled edges of said plates and the sides of said grooves, and means for holding said plates in position in said grooves comprising a series of members abutting end to end 10 and abutting said plates.

3. The combination with the door posts of a box car, of a door closure disposed therebetween comprising a lower door section, laterally movable plates extending longitudinally at each side thereof, the side edges of said plates being beveled at their front portions and said door posts being provided with longitudinally extended vertical grooves having inclined front portions with 20 which said plates are adapted to co-operate,

whereby a cam action occurs between said beveled edges of said plates and the sides of said grooves, an oblong rotatable member mounted on said section, a handle for turning said member, 25 slideable members at each side of said rotatable member respectively connected to and abutting said plates and in the same plane as said rotatable member, a link pivoted to said rotatable member at each side of said handle by a lost-motion connection and pivoted at its other end to the respective slideable member, said rotatable member being arranged to abut said slideable members when turned with its long axis in line therewith whereby said plates will be 30 held separated with said plates, slideable members and rotatable member in abutting relation.

In testimony whereof I affix my signature.
HERBERT S. NESBITT.
